Specification for Design.

Patented July 15, 1919.

Application filed April 19, 1919. Serial No. 291,391. Term of patent 14 years.

To all whom it may concern:

Be it known that I, ROBERT D. PIKE, a citizen of the United States, residing at the city and county of San Francisco, State of California, have invented a new, original, and ornamental Design for Multiple Display-Holders, of which the following is a specification, reference being had to the accompanying drawing, forming part thereof, wherein—

Figure 1 is a plan view of a multiple display holder, showing my new design.

Fig. 2 is an elevational view thereof.

I claim:—

The ornamental design for a multiple display holder, as shown.

In witness whereof I have signed my name to this specification in the presence of two witnesses.

ROBERT D. PIKE.
